CLAIM

The ornamental design for a barbecue grill, as shown and described.

DESCRIPTION

FIG. 1 is a front perspective view of a barbecue grill showing our new design;

FIG. 2 is a top plan view thereof;

FIG. 3 is a rear elevational view thereof;

FIG. 4 is a right side elevational view thereof;

FIG. 5 is a bottom plan view thereof;

FIG. 6 is an enlarged fragmentary view of the support member; and

FIG. 7 is an enlarged fragmentary perspective view of the opposite side of FIG. 6.
